UNITED STATES PATENT OFFICE.

JOHN SOMMER, OF PEORIA, ILLINOIS.

SPOOL-CARRIER.

SPECIFICATION forming part of Letters Patent No. 637,901, dated November 28, 1899.

Application filed February 23, 1899. Serial No. 706,617. (No model.)

To all whom it may concern:

Be it known that I, JOHN SOMMER, a citizen of the United States, residing at Peoria, in the county of Peoria and State of Illinois, 5 have invented certain new and useful Improvements in Spool-Carriers; and I do hereby declare that the following is a full, clear, and exact description of the invention, which will enable others skilled in the art to which it appertains to make and use the same.

My invention relates to spool-carriers; and my object is to facilitate the construction, improve the efficiency, and increase the durability of the same.

15 My improvement relates generally, as above-mentioned, to spool-carriers, and is designed to provide a support for the spool to hold it in the proper position in connection with the machine to which it is designed to deliver a 20 strand that is wound thereon and to provide a tension upon said strand by friction-bearing means and also to provide a convenient manner of placing the spool in the support and for detaching the same. The particular 25 application I make of the spool-carrier is in connection with a frame in which a spool or spools are designed to be carried and a frame rotated to prevent the twisting of wires together or to compensate for the twisting of 30 wires together to form a cable by separate means by turning the spools in the frame the same number of revolutions that are made by the machines that make the twist to form the cable.

35 My particular application of a frame used for the purpose I specify may be seen by reference to the application for Letters Patent of Peter Sommer, John Sommer, and Peter W. Sommer, filed the 3d day of February, 1894, 40 and bearing Serial No. 499,016, to which application I am a party.

45 My invention consists in the provision of a fixed bearing for the rims of each spool, and of an adjustable bearing acting in connection with the fixed bearing to support the spool.

That my invention may be more fully understood, reference is had to the accompanying drawings, in which—

Figure 1 shows a side elevation of the spool-supporting frame. Fig. 2 is a plan view of the same. Fig. 3 is a section through the line X X of Fig. 2. Fig. 4 is a detail view.

In the figures, A is a rectangular frame. A' and A² are journals upon the ends of said frame. a a are perforations through said journals.

B B is an S-shaped frame.

B' B² are oppositely-curved portions of the S-shaped frame.

C C C are the rims of the spools designed to be supported within the frame, which said spools are carried, respectively, in the opposite curves of the S-shaped portion of the frame.

D D are plates hinged to the curved portions of the S-frame and bearing against the ends of the spools.

E E are bearing-plates fixed upon the ends of the plates D D and are formed to match with the circumferences of the rims of the spools and to bear thereon or to be supported in substantially a bearing relation therewith.

F F F are bolts fixed in the said portions of the frame A, as best shown in Fig. 3 of the drawings, the said bolts extending out from the said frame some little distance and bearing through perforations in the plates D.

f f are coiled springs bearing between and against, respectively, the heads of the bolts and outside faces of the plates D, substantially in the manner shown in the drawings, and are provided to hold the hinged plates D in bearing relation against the ends of the spools and the bearing-plates E in proper position with relation to the rims of said spools to assist, in conjunction with the curved portions of the S-frame, in supporting the said spools as they are revolved with the frame A and also to enable the said plates D a sufficient lateral swinging from their hinges to free the bearing-plates E from contact with the rims of the spools to facilitate in the removal of the spools from the frame and in the placing of the same therein.

I desire to call the attention of the Office to a former application for patent by myself upon which Letters Patent No. 546,358 were issued upon the 17th day of September, 1895, in which I show the means for supporting spools in a frame and turning them across their axes within the said frame and also supporting them to turn upon their axes under frictional bearing upon the rims thereof.

to provide a tension for a strand being delivered therefrom. In my present application I show another means of accomplishing the same result.

5. The operation of the device is very simple. The spools containing strands having been properly deposited within the framework, the wire strands from said spools are carried forwardly and passing through the perforations 10 *a a* in the journal *A²*, and the strands being drawn out a tension will be obtained thereon as a result of the frictional contact of the rims of the spools with their supports. The supply of strand upon the spools having been 15 exhausted, they may be removed (or either one of them) by simply shifting the plates *D* laterally to remove the rim-bearing plates *E E* from contact with the frames, when the spool may be withdrawn from the frame. A 20 spool is deposited in the frame in the same manner—that is, by the same manipulation of the adjustable plates.

Having thus fully described my invention, what I claim, and desire to secure by Letters 25 Patent, is—

1. In a spool-carrier, the combination, with a revoluble frame, having curved bearing-surfaces, for supporting the rims of a spool, or for bearing against a portion of the circumferences thereof, and of laterally-adjustable plates hinged to the said curved plates for engaging portions of the rims on opposite sides from the said curved supporting-plates, and means for holding the said laterally-adjustable plates in position for bearing upon the spool-rims but allowing them to be moved laterally to release the said rims.

2. In a spool-carrier, the combination, with a revoluble frame of two bearing-plates for 40 supporting a spool upon its rims, located upon the opposite sides thereof, one fixed with relation to the frame and one movable with relation to the rims of the spool a supporting-plate bearing across the axis of the spool and 45 hinged to the fixed plate.

3. In a spool-carrier, the combination with an **S**-shaped frame, the curved portions of which are adapted to bear against a portion of the spool-rims, of plates hinged to the **S**- 50 rim and adapted to engage portions of the circumferences of the spool-rims upon the opposite sides and adapted to be adjusted with relation to the rims of the said spools.

4. In a spool-carrier, the combination with 55 a revoluble frame provided with a journal at each end, of a fixed curved plate adapted to receive and support the rim of a spool on one side and an adjustable plate adapted to support the rim of the spool on the opposite side 60 from the fixed plate and means for holding the adjustable plate under a yielding tension to hold it in place to support the spool-rim and yield under pressure to permit the removal of the spool.

65 5. In a spool-carrier, the combination with a frame provided with a journal at each end and revoluble at right angle with the direc-

tion of rotation of the spool adapted to be supported therein, of a curved bearing-face for supporting the rim of a spool, a laterally-adjustable plate, and means connected with said adjustable plate to support it in such adjustable relation with the rim of a spool, all substantially as described and shown.

6. In a spool-carrier, the combination with 75 a fixed curved plate supported in a frame revoluble at right angle with the direction of rotation of the spool adapted and to be supported therein, adapted to support the rim of a spool on one side, of a laterally-adjustable plate 80 adapted to support the spool upon the opposite side and to be moved laterally to release the spool-rim to permit its removal or the placing of the spool in position to be supported by the plates, all substantially as described and 85 shown.

7. In a spool-carrier, the combination with a revoluble frame provided with a journal at each end, one of which has a perforation there-through, of a fixed curved plate adapted to 90 support the rim of a spool on one side and a laterally-adjustable plate adapted to support the rim of a spool on the opposite side and to be moved laterally to release the spool-rim to permit its removal or the placing of a spool 95 in position in the frame to be supported by the plates, all substantially as described and shown.

8. In a spool-carrier, the combination with an **S**-shaped frame the curved portions of 100 which are adapted to bear against a portion of the spool-rims, of adjustable plates adapted to engage portions of the circumferences of the spool-rims on the opposite sides and suitable yielding mechanism for holding the 105 plates under tension in position to support the spool-rims but adapted to yield under pressure to allow the plates to be shifted, all substantially as described and shown.

9. In a spool-carrier, the combination with 110 the fixed curved plate *B'* adapted to support the rim of a spool on one side of the laterally-adjustable curved plate *E*, adapted to support the spool on the opposite side, and the plate *D*, connected with the curved plate *E*, 115 and hinged to the fixed curved plate *B'* and yielding mechanism for holding curved plate *E*, under tension in position to support the spool-rim but adapted to yield under pressure to allow the plate to be shifted, all substantially as described and shown.

10. In a spool-carrier, the combination with the revoluble frame *A* of the curved plates *B'*, *B²*, adapted to support the rims of spools 125 on one side, the laterally-adjustable plates *E*, *E*, adapted to support the rims of the spools on the opposite side, the plates *D*, *D*, connected each with one of the plates *E*, and hinged to the curved plates *B'*, *B²*, and mechanism for holding curved plates *E*, under tension in 130 position to support the spool-rim but adapted to yield under pressure to allow the plate to be shifted, all substantially as described and shown.

11. In a spool-carrier, the combination with the revolute frame A, provided with journal A' at its rear end and the journal A² at its forward end having the wire-delivery passages a, a, therethrough, of the fixed curved plates B', B², adapted to support the rims of spools on one side, the laterally-adjustable plates E, E, adapted to support the rims of the spools on the opposite side and suitable mechanism for supporting the adjustable plates E, E, and for holding the same under tension to support the spool-rims but adapted to yield under pressure to allow the plates to be shifted, all substantially as described and shown.

12. In a spool-carrier, the combination with the revolute frame A, provided with journal A' at its rear end and the journal A² at its forward end having the wire-delivery passages a, a, therethrough, of the fixed curved plates B', B² adapted to support the rims of spools on one side, the laterally-adjustable plates E, E, adapted to support the rims of

the spools on the opposite side, the plates D, D, connected each with one of the plates E ²⁵ and hinged to the curved plates B', B² and the set-screw F F F F, bearing through the perforations in plates D, and being fixed upon the frame A, and the spring f f f f, intervening between the face of the plates D and the ³⁰ heads of the set-screws, all substantially as described and shown.

13. In a spool-carrier, the combination with the fixed curved plate B' of the plate D, hinged thereto, the curved plate E, fixed to plate D, ³⁵ the set-screw F F bearing through the perforations in plates D, and the spring f f, intervening between the heads of the set-screws and the face of plates D, all substantially as described and shown.

In testimony whereof I affix my signature in presence of two witnesses.

JOHN SOMMER.
